PROCESS FOR DEAERATING LIQUIDS

Chester H. Goodwin, Nitro, W. Va., assignor to
 American Viscose Corporation, Wilmington,
 Del., a corporation of Delaware

Application June 13, 1946, Serial No. 676,475

2 Claims. (Cl. 18—54)

1

The present invention relates to a process for preparing viscose or other material for spinning into filaments, films, sheets and the like, and is particularly concerned with the removal of gas bubbles from the material preliminary to such spinning or other forming operations.

In the preparation of viscose and other film and filament-forming materials, the mechanical agitation thereof that is effected by stirring and mixing agitator blades as well as that agitation which results from hydraulic turbulence during transfer from one tank to another introduce considerable amounts up to 10% by volume of gas bubbles into the material. For the purpose of definition, the expression "mechanical agitation" used hereinafter in both the description and the claims is intended to include that produced by hydraulic conditions of turbulence, the entrapping of gas by vortex action and gas entrained from the walls of vessels and pipe lines. Another source of gas bubble formation is the development of CS_2 vapor in the case of viscose, and solvent vapors in the case of solutions of cellulose organic derivatives or vinyl resins in volatile organic solvents.

Heretofore the deaeration of viscose and similar spinning or forming materials containing substantial amounts of gas bubbles as a result of previous mechanical agitation thereof has generally been effected by placing the material within a tank or other vessel and evacuating the vessel. This procedure required a plurality of tanks when a continuous spinning or forming procedure is desired, in order that while one of the tanks is being evacuated or deaerated by vacuum, at least one other tank is available to supply the material to the spinnerets or other forming units and yet another is being filled. Special care has to be taken during the discharge of the material from the deaerating tank that no air is entrained by the vortex developed at the bottom of the tank when the level therein becomes low. In order to prevent such inclusion of air bubbles it has been common practice to allow a residue or "heel" to remain in the bottom of the tank, which must then either be thrown away or mixed with the next batch introduced into the tank. Various systems have been proposed to overcome this difficulty, but they all require auxiliary equipment or special handling operations.

Experience has shown that while deleterious effects result from the presence during spinning of fairly large gas bubbles, dissolved gas or a limited number of bubbles of .01" or less diameter have little or no effect. In accordance with the

2

invention of my above-mentioned copending application, the material to be formed is divested of gas bubbles by continuously passing it through a chamber the contents of which are maintained under a pressure of about 20 to 5000 pounds per square inch gage at a sufficiently slow rate relative to the volume of material normally in the chamber that any unit of the material is completely free of bubbles before it leaves the chamber. The period of hold-over necessary is inversely proportional to the pressure and in general is at least about five minutes. For the most practical operating range, a pressure between about 25 and 600 pounds per square inch is preferred. By effecting bubble solution in this manner, a single continuous treating vessel can be used, thus saving space and equipment, and the problem of heels or tank bottoms or residues is entirely eliminated, thus reducing the amount of care and attention, as well as any auxiliary equipment normally used to take care of heels, while improving the uniformity of the product.

In accordance with the present improvement, the material to be deaerated or degasified is forced through a relatively narrow passage which has portions thereof doubled back upon other portions thereof. The doubled-back portions may lie within, around, or adjacent the other portions. Passage through a narrow channel has the advantage over that through a tank in that a higher velocity can be maintained throughout the cross-section of the channel. The narrow channel assures that the surfaces of the channel are continuously swept clean, even of highly viscous material, so that no skin or thin lining can form from relatively stagnant material thereon. Also, the doubling back provides adequate length and time of travel even at high velocity to assure complete deaeration in a compact unit of equipment. Other objects and advantages will be apparent from the drawing, in which illustrative embodiments are shown.

In the drawings:

Figure 1 shows a longitudinal section of a preferred arrangement of equipment for accomplishing the objects of the invention.

Figure 2 is a longitudinal section of a modification, and

Figure 3 is a longitudinal section of another modification.

The invention will be described particularly with reference to the handling of viscose for the production of filaments, films and the like, but it is to be understood that the general arrangement is applicable as well to the handling of other

filament or filament-forming materials, or in fact to other materials which are intended to be formed by extruding continuously into rods, tubes, plates and the like.

As shown in Figure 1, the viscose may be supplied by a line 2 from the discharge side of the filters or from storage vessels, such as spinning tanks and is forced, such as by any suitable pump 3, into the pipe 4 which serves to feed the viscose into one end of the deaerating unit generally indicated by the numeral 5. This unit comprises a concentric set of conduits 6, 7, and 8 providing a long relatively narrow channel having portions doubled back on an adjacent portion into contiguous relationship with a single wall thickness therebetween. The viscose flows into the open end of the large conduit 6, passes through the annular channel between the internal surface of pipe 6 and the external surface of pipe 7, and is caused to double back by the end wall 9 so that it then flows within the annular channel between the internal surface of pipe 7 and the external surface of pipe 8. At the other end of this pipe 7, the wall 10 forces the viscose to flow into the central pipe 8 by which it is discharged, either to storage tanks or, if desired, to the forming stations of spinning or film-forming machines. A regulating valve 11 capable of maintaining a constant inlet pressure may be provided in pipe 8, as shown, in order to maintain the desired pressure in the deaerating unit. This regulating valve may be omitted whenever the nature of the outlets from pipe 8 is such as to maintain sufficient pressure without aid. Thus, under proper conditions, the orifices of the spinnerets in one or more spinning machines supplied by line 8 may develop and maintain sufficient pressure to accomplish complete deaeration without necessitating the use of the regulating valve 11. While three pipes are shown, two, four, five, or more may be used. When an even number are used, the viscose will be discharged from the same end of the unit as it enters, though, of course, through a separate conduit.

In Figure 2, the viscose enters the deaerating unit 5a through pipe 4a, flows within the outer annular passage inside pipe 6a, is doubled back by an arcuate end wall 9a, returns within the annular channel inside pipe 7a, and is deflected into pipe 8a by the end wall 10a having a central cusp or peak 15. To streamline the flow and prevent stagnating regions in the viscose passing from pipe 4a to the outer channel in pipe 6a, a conical cap 100 may be secured externally of the wall 10a. While this embodiment is somewhat more expensive to construct, it has the advantage of streamlining the flow of viscose throughout the narrow passage. In this embodiment as well as in that of Figure 1, the direction of flow may be reversed so that it passes first through the central pipe and last through the outermost annular portion of the channel.

In Figure 3, there is shown a deaerating unit 5b with a channel of substantially constant cross-section having a plurality of adjacent or contiguous sections or portions 20, 30, 40, 50 and 60 having a single wall thickness therebetween and being connected at their ends by the curved portions 21, 31, 41 and 51. The viscose enters by pipe 4b and is discharged from pipe 60 through a regulating valve or through pressure-maintaining devices, such as spinning machines and the like. Any shape of cross-section, circular, square, rectangular or oval may be used for the channel of the unit 5b.

The pressure that may be employed in the deaeration units may vary from 20 to 5000 pounds per square inch gage or higher. Generally, the pressure will depend upon the time required for a given portion of the viscose to pass through the channel of the unit and upon the properties of the specific viscose or other material involved. For example, if the unit is made of such size with respect to the rate of consumption of a viscose having normal spinning properties that any given portion of the viscose takes about six hours to pass through the unit, a pressure of 20 to 25 pounds per square inch gage is generally adequate. However, if the capacity of the pressure unit is so small relative to the rate of passage of the viscose therethrough that only one hour is taken for such passage, a pressure of 90 to 100 pounds per square inch gage may be required.

As stated, the pressure depends somewhat upon the particular material being handled and for each particular material an equation may be established which will enable the operator to determine the time period required for any given pressure. Thus, there may be used the equation:

$$T = \frac{a}{P} + b$$

where

T is the time in minutes

P is the pressure in pounds per square inch gage

a is a constant

b is a constant

By determining the times and pressures for two or more spaced points along a curve representing such an equation, the constant a can be determined from the slope of the curve and the constant b from its intercept with the ordinate axis. For example, a viscose containing 6.6% caustic soda and 8% cellulose at 18° C. was found to have a constant a equal to 4860 and b equal to 5.71. The times obtained by substitution in this equation are minimum values and it is advisable to add a small period as a precaution to assure complete disappearance of bubbles. Similar equations can be readily established for each material being worked with, in order to get the proper period of time that the substances must be held at a given pressure.

Preferably the cross-section of the pressure channel throughout its length in the deaerating unit is approximately the same and this is easily obtainable with the construction shown in Figure 3, but may require odd-sized pipes in the embodiments of Figures 1 and 2. Conveniently, therefore, the embodiments of Figures 1 and 2 may depart considerably from a channel of constant cross-section throughout. For example, they could be made of standard 4-inch, 6-inch, and 8-inch diameter pipes with a total length of passage of 65 feet. When forcing a viscose through at a rate of 600 cubic inches per minute, a passage time of at least 45 minutes is obtained and the pressure should be maintained well above 100 pounds per square inch gage.

It will be understood that changes and modifications may be made without departing from the spirit and scope of the invention as described in the appended claims.

I claim:

1. A process for divesting of bubbles a forming material, of viscose, containing substantial amounts of gas bubbles comprising continuously passing the material in streamlined flow through a narrow channel free of stagnating regions and having portions doubled back on other portions

thereof having a sufficiently long passage with respect to the volumetric rate of flow that passage through the channel requires at least seven minutes, and maintaining the material within the channel under a pressure of 20 to 5000 pounds per square inch gage, the pressure and time of passage being correlated to effect substantially complete disappearance of the gas phase prior to discharge from the chamber.

2. A process for divesting of bubbles a forming material of viscose containing substantial amounts of gas bubbles comprising continuously passing the material in streamlined flow through a narrow channel free of stagnating regions and having portions doubled back on other portions thereof having a sufficiently long passage with respect to the volumetric rate of flow that passage through the channel requires at least thirty minutes, and maintaining the material within the channel under a pressure of 25 to 600 pounds per square inch gage, the pressure and time of

passage being correlated to effect substantially complete disappearance of the gas phase prior to discharge from the chamber.
